CLAIM

The ornamental design of a carrying device for babies, as shown and described.

DESCRIPTION

FIG. 1 is a perspective view of a carrying device for babies in accordance with the present invention;

FIG. 2 is a front elevational view thereof;

FIG. 3 is a rear elevational view thereof;

FIG. 4 is a side elevational view thereof;

FIG. 5 is a side elevational view;

FIG. 6 is a top plan view thereof; and,

FIG. 7 is a bottom plan view thereof.

The broken lines in the drawings depict portions of the carrying device for babies that form no part of the claim.
